(57) **CLAIM**

The ornamental design for a compact disc rack, as shown and described.

DESCRIPTION

FIG. 1 is a front perspective view.

FIG. 2 is a side perspective view.

FIG. 3 is a left side view on a reduced scale with respect to FIGS. 1 and 2; the right side being a mirror image.

FIG. 4 is a front, elevational view on a reduced scale with respect to FIGS. 1 and 2.

FIG. 5 is a top view on a reduced scale with respect to FIGS. 1 and 2; the bottom view being a mirror image.

FIG. 6 is a rear, elevational view on a reduced scale with respect to FIGS. 1 and 2.

FIG. 7 is a perspective view of a second embodiment of that shown in FIGS. 1-6, the only difference being in the additional shelf.
